UNITED STATES PATENT OFFICE.

FREDERICK FRANCIS FECHER, OF BROOKLYN, NEW YORK, ASSIGNOR TO BECK
DUPLICATOR COMPANY, A CORPORATION OF NEW YORK.

DUPLICATING-MACHINE.

1,222,275.

Specification of Letters Patent. Patented Apr. 10, 1917.

Application filed October 25, 1913. Serial No. 797,282.

To all whom it may concern:

Be it known that I, FREDERICK FRANCIS FECHER, a citizen of the United States, and a resident of the borough of Brooklyn, in the 5 city and State of New York, have invented certain new and useful Improvements in Duplicating-Machines, of which the following is a specification.

My invention relates to duplicating machines, and particularly to that type of such machines which are provided with an adhesive duplicating surface adapted to receive negative or reversed impressions, of matter to be duplicated.

15 The invention relates particularly to means co-acting with such a duplicating surface, for the purpose of applying thereto paper or the like, upon which a positive impression of the matter to be duplicated is to 20 be transferred from the duplicating surface.

One of the principal objects of the invention is to provide means whereby the operation of transferring a number of successive positive impressions from the duplicating 25 surface to the paper or the like provided to receive the same, may be performed more efficiently, quickly and easily than is possible by means of methods now known in the art.

The invention consists in the novel construction, arrangement and combination of 30 various devices and parts, as hereinafter more particularly described.

In the accompanying drawings, Figure 1 is a plan view of my invention certain portions 35 being broken away, Fig. 2 is a vertical section thereof, and Fig. 3 is a plan view of a portion thereof on an enlarged scale.

Duplicating machines of the type of which my invention is an example, are usually supported upon a base, or are contained in a case or box provided with sides. In using 40 my invention, it is desirable to provide the base or casing of the machine with tracks or guideways, the upper edges of which are provided with flanges projecting inwardly at about a right angle. I have not thought it necessary to show in the accompanying drawings the base or casing of the duplicating machine, but I have shown a portion of 45 the flanged track or guideway on each side of the machine, the same being designated by the reference numeral 14.

In the embodiment of my invention which I have selected for the purpose of illustration 50 in the accompanying drawings and descrip-

tion in this specification, I provide members 16, preferably of bent sheet metal, adapted to slide on the flanges or tracks 14. These tracks or flanges 14 are rigidly secured to the base of the machine. In Fig. 2 I have 60 shown the duplicating surface, numbering the same 100. If desired, for the purpose of minimizing friction, said sliding members 16 may be provided with wheels 17 which are adapted to bear against the inner edge of 65 the flanges of the said tracks 14. These members 16 are rigidly secured to a rod 20. Journaled on the rod 20, inside of the members 16, are L-shaped members 13. At the upper extremities of these L-shaped members 13 is detachably pivotally secured a roller 15, by means of pins 40 which pass through openings in the L-shaped members 13 and into sockets in the ends of the roller 15. This roller is adapted to bear a roll of 70 paper 43 which may be unwound therefrom and wound upon another roller 19, which is journaled at the other extremities 41 of the 75 above-mentioned L-shaped members 13.

I also provide a handle 22, preferably 80 formed of a rod whose center portion is substantially parallel to the roller 15, each end portion thereof being bent at right angles to the center portion and pivotally secured to the rod 20 at a point thereon inside of the 85 L-shaped members 13, by means of enlarged or flattened attached members 23.

Pivotally secured to these members 23 are L-shaped members 24, the shorter arms of 90 which are provided with studs 25, and in the longer arms of which is journaled a roller 27. Springs 26 have one end secured to the rod 20 and the other end to the studs 25, and tend to hold said roller 27 in contact with the paper wound on the roller 19. 95

Tensional means may be provided to prevent too rapid unwinding of the paper on the roller 15. These means may have the usual or any suitable form, those shown in the drawings consisting of spring pressed fingers 28, carrying a metal strip 29, which bears on the roller 15. 100

The operation of my invention is as follows:

The roller 15 is removed from the apparatus by withdrawing the pins in the ends thereof. On this roller is slipped a roll of paper or the like on to which it is desired to transfer a number of images from the duplicating surface, and the roller is re- 110

placed in the machine so that the paper will feed over the top of the roller. The tensional device is now allowed to bear on the roller to prevent too rapid unwinding of the paper thereon. The end of the paper is now passed between the rollers 19 and 27 and rolled a few times around the roller 19, to insure against its unwinding. The apparatus is now ready for use.

When it is desired to print a number of impressions from the duplicating surface on to the paper in the paper-carrying device, it is placed on the duplicating machine in such a manner that the members 16 will slide on the tracks 14. The bottom of the roller 19 and the surface of the paper thereon, will now rest on the printing surface of the duplicating machine. The device is placed at one end of the tracks 14, and drawn to the other end, while a downward pressure is maintained on the handle 22, insuring contact between the duplicating surface and the paper on the roller 19.

As the device is drawn over the duplicating surface the impression from the same is transferred to the paper on the lower side of the roller 19, and at the same time the paper is wound around the roller as fast as printed. As a quick drying ink is always used with devices of this character, no blurring occurs, even though the paper be rewound immediately after the impression is taken thereon. When the device has been run entirely across the printing surface, the handle is raised, thus removing the paper on the roller 19 from the printing surface. The device is then run back to the other end of the duplicating surface, and the operation repeated as many times as may be desired. As the paper becomes wound around the roller 19, it is kept from slipping by the roller 27, which is continually forced against the roller 19 and the paper thereon by the action of the springs 26.

The principal advantage of my invention lies in the increased ease and speed with which impressions may be taken over the old process of placing the paper on the duplicating surface, by hand or otherwise, one sheet at a time. Another advantage of the invention is that the rolling of the paper around the take-up roller neutralizes the tendency of the paper to curl up as a result of its application to the duplicating surface, so that the paper when finally taken from the roll lies flat or nearly so.

Having thus described my invention what I claim as new and desire to secure by Letters Patent is as follows:

1. A duplicating machine comprising a duplicating surface, devices adapted to bring paper into contact with said duplicating surface; said devices comprising a roller adapted to hold a roll of paper, a second roller adapted to maintain said paper

in contact with said duplicating surface while an impression is transferred from said surface to said paper, said paper being wound around said second roller after having received said impression and stored thereupon; and means adapted to move said devices across said duplicating surface. 70

2. A duplicating machine, comprising a duplicating surface, devices adapted to bring paper into contact with said duplicating surface; said devices comprising a roller adapted to hold a roll of paper, tensional devices adapted to prevent the too rapid unwinding of said paper, a second roller adapted to maintain said paper in contact with said duplicating surface while an impression is transferred from said surface to said paper, said paper being wound around said second roller after having received said impression and stored thereupon; and means adapted to move said devices across said duplicating surface. 75

3. A duplicating machine, comprising a duplicating surface, devices adapted to bring paper into contact with said duplicating surface; said devices comprising a roller adapted to hold a roll of paper, a second roller adapted to maintain said paper in contact with said duplicating surface while an impression is transferred from said surface to said paper, said paper being wound around said second roller after having received said impression and stored thereupon; tensional means adapted to bear against said second roller to prevent the paper thereon from slipping, and means adapted to move said devices across said duplicating surface. 90

4. In a duplicating machine, the combination with a duplicating surface and a guide, of a member adapted to roll on said guide, 105 and devices mounted on said rolling member adapted to bring paper into contact with said duplicating surface; said devices comprising a roller adapted to hold a roll of paper, a second roller adapted to maintain said paper in contact with said duplicating surface while an impression is transferred from said surface to said paper, said paper being wound around and stored upon said second named roller after it has received the 115 impression; and means adapted to move said rolling member across said duplicating surface.

5. In a duplicating machine, the combination with a duplicating surface, and a guide, 120 of a movable member, adapted to run on said guide; a member mounted on said movable member adapted to bear a roll of paper, and a roller mounted on said movable member adapted to bring said paper into contact 125 with said duplicating surface, while an impression is transferred from said surface to said paper, said paper being wound around said roller after having received the impression and stored thereupon. 130

6. In a duplicating machine, the combination with a duplicating surface and a guide, of a movable member adapted to run on said guide, a member mounted on said movable member and adapted to bear a roll of paper, tensional means adapted to prevent the too rapid unwinding of said paper, and a roller mounted on said movable member and adapted to bring said paper into contact with said duplicating surface while an impression is transferred from said surface to said paper, said paper being wound around said roller after having received the impression and stored thereupon.
- 10 7. In a duplicating machine, the combination with a duplicating surface and a guide, of a movable member adapted to run on said guide, a member mounted on said movable member and adapted to bear a roll of paper, of a roller mounted on said movable member adapted to bring said paper into contact with said duplicating surface while an impression is transferred from said surface to said paper, said paper being wound 25 around said roller after having received the impression and stored thereupon, and tensional means adapted to bear against said roller to prevent the paper thereon from slipping.
- 20 8. In a duplicating machine, the combination with a duplicating surface and a guide, of a movable member adapted to run on said guide, a roller mounted on said movable member and adapted to bear a roll of paper, a second roller mounted on said movable member adapted to bring said paper into contact with said duplicating surface while an impression is transferred from said surface to said paper, said paper being wound 35 around said second roller after having received said impression and stored thereupon, means adapted to move said rollers across said duplicating surface, and tensional means adapted to prevent said paper from slipping.
- 40 9. In a duplicating machine, the combination with a duplicating surface and a guide, of a movable member adapted to run on said guide, a roller mounted on said movable member and adapted to bear a roll of paper, a second roller mounted on said movable member adapted to bring said paper into contact with said duplicating surface while an impression is transferred from said surface to said paper, said paper being wound 55 around said second roller after having received the impression and stored thereupon, and means adapted to move said rollers across said duplicating surface.
- 50 10. In a device of the character described, the combination with a carriage slidably mounted on a duplicating machine, provided with a duplicating surface, of a roller on said carriage adapted to bear a roll of paper, a second roller adapted to bring said paper
- 60 into contact with the duplicating surface of said duplicating machine, whereby an impression is transferred from said surface to said paper, said paper being wound around said second roller after having received said impression and stored thereupon.
- 70 11. In a device of the character described, the combination with a carriage detachably slidably mounted on a duplicating machine provided with a duplicating surface, of a roller on said carriage adapted to bear a roll of paper, and a second roller adapted to bring said paper into contact with the duplicating surface of said duplicating machine, whereby an impression is transferred 75 from said surface to said paper, said paper being wound around said second roller after having received the impression, and stored thereupon.
- 80 12. In a device of the character described, the combination with a carriage slidably mounted on a duplicating machine provided with a duplicating surface, of a roller on said carriage adapted to bear a roll of paper, tensional means adapted to bear against said roller, whereby too rapid unwinding of the paper is prevented, and a second roller adapted to bring said paper into contact with the duplicating surface of said duplicating machine, whereby an impression is 85 transferred from said surface to said paper, said paper being wound around said second roller after having received the impression and stored thereupon.
- 90 13. In a device of the character described, the combination with a carriage detachably slidably mounted on a duplicating machine provided with a duplicating surface, of a roller on said carriage adapted to bear a roll of paper, tensional means adapted to bear against said roller, whereby too rapid unwinding of the paper is prevented, and a second roller adapted to bring said paper into contact with the duplicating surface of said duplicating machine, whereby an impression is 95 transferred from said surface to said paper, said paper being wound around said second roller after having received the impression and stored thereupon.
- 100 14. In a device of the character described, the combination with a carriage slidably mounted on a duplicating machine provided with a duplicating surface, of a roller on said carriage adapted to bear a roll of paper, a second roller adapted to bring said paper 105 into contact with the duplicating surface of said duplicating machine, whereby an impression is transferred from said surface to said paper, said paper being wound around said second roller after having received the impression and stored thereupon.
- 110 15. In a device of the character described, the combination with a carriage slidably mounted on a duplicating machine provided with a duplicating surface, of a roller on said carriage adapted to bear a roll of paper, a second roller adapted to bear against said second named roller, to prevent the paper thereon from slipping.
- 120 16. In a device of the character described, the combination with a carriage slidably mounted on a duplicating machine provided with a duplicating surface, of a roller on said carriage adapted to bear a roll of paper, a second roller adapted to bear against said second named roller, to prevent the paper thereon from slipping.
- 125 17. In a device of the character described, the combination with a carriage slidably mounted on a duplicating machine provided with a duplicating surface, of a roller on said carriage adapted to bear a roll of paper, a second roller adapted to bear against said second named roller, to prevent the paper thereon from slipping.
- 130 18. In a device of the character described, the combination with a carriage slidably mounted on a duplicating machine provided with a duplicating surface, of a roller on said carriage adapted to bear a roll of paper, a second roller adapted to bear against said second named roller, to prevent the paper thereon from slipping.

the combination with a carriage detachably slidably mounted on a duplicating machine provided with a duplicating surface, of a roller on said carriage adapted to bear a roll 5 of paper, a second roller adapted to bring said paper into contact with the duplicating surface of said duplicating machine, whereby an impression is transferred from said surface to said paper, said paper being 10 wound around said second roller after having received the impression and stored thereupon, and tensional means adapted to bear against said second named roller to prevent the paper thereon from slipping.

15 16. In a device of the character described, the combination with a carriage slidably mounted on a duplicating machine provided with a duplicating surface, of a roller on said carriage adapted to bear a roll of paper, 20 a second roller adapted to bring said paper into contact with the duplicating surface of said duplicating machine, whereby an impression is transferred from said surface to said paper, said paper being wound around 25 said second roller after having received the

impression and stored thereupon; and means adapted to draw said carriage across said duplicating machine.

17. In a device of the character described, the combination with a carriage detachably 30 slidably mounted on a duplicating machine provided with a duplicating surface, of a roller on said carriage adapted to bear a roll of paper, a second roller adapted to bring paper into contact with the duplicating surface of said duplicating machine, whereby an impression is transferred from said surface to said paper, said paper being wound around 35 said second roller after having received the impression and stored thereupon; and means 40 adapted to draw said carriage across said duplicating machine.

In witness whereof I have hereunto signed my name this 24th day of October 1913, in the presence of two subscribing witnesses.

FREDERICK FRANCIS FECHER.
